Atty.

UNITED STATES PATENT OFFICE.

HUGH M. STOLLER, OF NEW YORK, N. Y., ASSIGNOR TO WESTERN ELECTRIC COMPANY, INCORPORATED, OF NEW YORK, N. Y., A CORPORATION OF NEW YORK.

ELECTRICAL IGNITION SYSTEM.

Application filed September 15, 1921. Serial No. 500,736.

To all whom it may concern:

Be it known that I, HUGH M. STOLLER, a citizen of the United States, residing at New York city, in the county of New York and State of New York, have invented certain new and useful Improvements in Electrical Ignition Systems, of which the following is a full, clear, concise, and exact description.

10 This invention relates to improvements in electrical ignition systems and more particularly to such systems employed for igniting the gaseous charges in internal combustion engines.

15 One of the objects of the invention is to provide an ignition system, energized by a current of relatively high voltage, which will deliver a spark only when the primary circuit is broken, and will not deliver a 20 spark when the said circuit is closed.

There are now in general use, electric power and light plants comprising an internal combustion engine and a dynamo driven thereby. In order to make the control circuits for such plants as economical and simple as possible, it has been the practice to supply the ignition system of the internal combustion engine with current from the dynamo. The current supplied by such 25 dynamos is generally under a pressure of approximately thirty-two volts or more, and, due to this potential, for reasons hereinafter explained, great difficulty has been encountered in preventing a spark being delivered the spark plug of the engine when the primary ignition circuit is made; this 30 spark occurring at a time too early in the cycle of the engine for efficient operation. This difficulty is obviated by the present invention which is an improvement upon the 35 invention disclosed in the copending application of Reddig, Serial No. 465,296, filed April 28, 1921.

In ignition systems employed in such 40 plants which comprise a primary circuit which is made and broken intermittently by an interrupter, and a secondary circuit inductively related to the primary circuit in which the spark plug of the engine is connected, the efficiency and life of the engines have been reduced, due to the presence of what is known in the art as "pre-

ignition". In the efficient operation of an internal combustion engine, the gaseous charge should be fully ignited at a time 55 when the piston has about completed its compression stroke and has just begun its working stroke, at which time the connecting rod has just passed dead center. If the charge is fully ignited before the piston has 60 reached this point in its cycle, the force of the explosion will be exerted there-against either while it is completing its compression stroke or is on dead center; in both cases lessening the effective working power of the 65 explosion and in the second case placing an undue strain on the connecting rod and crank shaft. Where a gaseous charge is ignited at such a time "preignition" is said to have taken place. Upon careful analysis it has been found that preignition which 70 has been prevalent in ignition systems of the type above referred to, has been caused by the creation of a spark at the plug when the interrupter closes the primary circuit. 75 In such ignition systems it is desired that a spark take place at the plug at the time when the interrupter breaks the primary circuit, and where such a spark occurs at the plug when the primary circuit is closed 80 by the interrupter, the charge is fired too early in the cycle of the engine. It is a primary object of the invention to provide an ignition system of this type which will prevent any spark occurring at the plug when 85 the interrupter closes the primary circuit, and will not increase to any substantial degree the potential required to be induced in the secondary circuit in order to produce a spark at the plug when the primary circuit is broken. To accomplish this object, 90

an ignition system made in accordance with the invention includes an asymmetric conductor such as an electron tube, a tungar rectifier, etc., in its secondary circuit, the 95 anode and cathode of which are so arranged with respect to the current flow that it prevents all current flow through said secondary circuit when the primary circuit is made and permits current to flow only when the 100 primary circuit is broken.

In the drawings, the figure illustrates a preferred embodiment of the invention.

Referring to the drawings in detail, the

reference numeral 1 indicates an internal combustion engine connected with a dynamo electric machine 2 by means of a shaft 3, the dynamo when in operation serving to energize a series of translating devices 4, and charge a storage battery 5. The dynamo 2 is provided with a shunt winding 6 and a series winding 7, thus making it a compound machine. Rotatably mounted upon the shaft 3, is a cam 8 having an extension 9 which cooperates with a contact 10 to periodically interrupt the primary circuit. A manual switch 11 serves as a means for starting and stopping the operation of the system.

A low tension primary winding 12 has in series therewith a resistance 13 to prevent an excess of current flow, and the filament 14 of an asymmetric two element conductor 20 or valve 15. When the interrupter closes its contact, a circuit through the primary winding 12 is established as follows: positive pole of dynamo 2, conductors 16, 17, and 18, winding 12, resistance 13, conductor 19, filament 14, conductor 20, cam 8, contacts 9 and 10, conductor 21, switch 11, conductors 22 and 23 to the negative terminal of the dynamo 2.

Inductively related to the primary winding 12 is a high tension secondary winding 24, through which a high voltage is impressed upon the electrodes of a spark plug 25. In series with the winding 24 is the plate 26 of the valve 15.

The operation of the system is as follows: When the primary circuit is made, the voltage induced in the secondary circuit is in the direction indicated by the dotted line arrow, and at this time no induced current can flow through the winding 24 because of the asymmetric action of valve 15, the characteristics of which are well known to those skilled in the art. When contact 9 leaves contact 10 and the circuit of winding 12 is accordingly broken, the voltage induced in secondary winding 24 is in the opposite direction, as indicated by the full line arrow, and produced a spark at the terminals of the plug 25 over the following circuit: winding 24, conductor 27, plate 26, filament 14, conductor 19, resistance 13, primary winding 12, conductor 18, 17, series field 7, battery 5, manual switch 11, conductors 22 and 28, through the frame of engine 1, spark plug 25, conductor 29, and back to the coil 24.

The necessity for providing the above described means for preventing pre-ignition is greater in cases of relatively high voltage ignition systems operating at thirty-two volts and over as compared with low voltage systems operating at twelve volts and under. In order to secure a satisfactory life of the breaker contacts 9 and 10, it is necessary to limit the inductance of the primary

winding 12 by employing a low resistance winding. It is, therefore, necessary to insert the resistance 13 to limit the primary current. The ratio of resistance to inductance in the primary circuit of such "high voltage" ignition systems, is, therefore, large, resulting in a relatively quick building up of current, and, therefore, of secondary voltage. Thus, in such "high voltage" systems, the ratio of the induced voltage in the secondary upon the make of the primary contacts, as compared to the break, is greater than in low voltage ignition systems.

The difficulties of securing proper ignition in prime mover dynamo plants are further increased at starting by the fact that the primary battery voltage is reduced by the heavy current required to crank the engine, the generator at that time operating as a motor. The tendency to pre-ignition is also increased toward the latter part of the charging period when the battery voltage and consequently the secondary voltage is high.

As is well known in the art, the potential required to break down a spark gap is much less at high temperatures and when the gap is located in a gas, such as is formed by the explosive mixture. It is obvious, however, that under starting conditions when the engine is cold and the explosive mixture is imperfectly vaporized, that the potential necessary to cause a spark to cross the gap at the spark plug will be very much greater than under running conditions when the engine is warmed up. The result is that the use of an asymmetric conductor of this type prevents ignition which would otherwise occur after the engine has warmed up, but at the same time consumes but a small proportion of the voltage of the secondary circuit which is especially advantageous under the conditions occurring at starting which require the maximum induced voltage in the secondary circuit.

Although this system is disclosed in connection with prime mover dynamo plants, its application is not to be considered as limited to such plants, but is to be defined solely by the scope of the appended claims.

What is claimed is:

1. In a system for preventing preignition in explosive engines, a low tension circuit including a source of current under pressure of a relatively high voltage and an interrupter, a high tension circuit in inductive relation to the low tension circuit and including a spark gap, and a hot cathode asymmetric conductor in the secondary circuit for passing currents resulting from the opening of the interrupter contacts.

2. In a prime mover dynamo plant in combination, a single cylinder internal combustion engine, a generator driven by the

engine, supply leads from the generator, an induction coil primary and an interrupter connected across the leads of the generator, a secondary in inductive relation to the primary, a spark plug, and a hot cathode asymmetric conductor in circuit with the secondary to prevent current passing there-

through upon the closure of the interrupter contacts.

In witness whereof, I hereunto subscribe 10
my name this 10th day of September A. D.,
1921.

HUGH M. STOLLER.
